DESIGN FOR A FENDER FLAP

Walter C. Jackson, Rahway, N. J., assignor to
Tingley-Reliance Rubber Corporation, Rahway,
N. J., a corporation of New Jersey

Application June 1, 1934, Serial No. 51,992

Term of patent 7 years

To all whom it may concern:

Be it known that I, WALTER C. JACKSON, a citizen of the United States, residing at Rahway, in the county of Union and State of New Jersey, have invented a new, original, and ornamental Design for Fender Flaps, of which the following is a specification, reference being had to the accompanying drawing, forming part thereof, wherein

Figure 1 is a face view of the fender flap;

Fig. 2 is a bottom edge view, and
Fig. 3 is a fragmentary enlarged longitudinal section, taken at about the plane indicated by the line 3—3 in Fig. 1.

I claim:

The ornamental design for a fender flap, as shown.

Signed at Rahway, New Jersey, this 26th day of May, 1934.

WALTER C. JACKSON.
